[57] CLAIM

The ornamental design for a connector mounting device for extending I/O connections to a personal computer, as shown and described.

DESCRIPTION

FIG. 1 is a perspective view of a connector mounting device for extending I/O connections to a personal computer showing my new design;

FIG. 2 is a top plan view thereof;

FIG. 3 is a front elevational view thereof;

FIG. 4 is a side elevational view thereof;

FIG. 5 is a bottom plan view thereof;

FIG. 6 is a rear elevational view thereof;

FIG. 7 is a perspective view of a second embodiment of
our design;

FIG. 8 is a top plan view thereof;

FIG. 9 is a front elevational view thereof;

FIG. 10 is a side elevational view thereof;

FIG. 11 is a bottom plan view thereof;

FIG. 12 is a rear elevational view thereof.
